UNITED STATES PATENT OFFICE.

JAMES M. NEIL, OF TORONTO, ONTARIO, CANADA, ASSIGNOR TO FREDERIC C. NORRIS,
TRUSTEE, OF DETROIT, MICHIGAN.

PROCESS FOR SEPARATING THE METALS CONTAINED IN COPPER-NICKEL MATTE.

No. 882,075.

Specification of Letters Patent. Patented March 17, 1908.

Application filed June 3, 1907. Serial No. 377,041.

To all whom it may concern:

Be it known that I, JAMES M. NEIL, of the city of Toronto, in the Province of Ontario, Canada, have invented certain new and useful Improvements in Processes for Separating the Metals Contained in Copper-Nickel Matte, of which the following is a specification.

My object is to devise means for separating the metals contained in copper-nickel matte which will be materially cheaper than the processes now in use, and I attain my object by a process which may be briefly summarized as follows:—The matte is by treatment with sulfuric acid converted into a solution of sulfates of the copper nickel and any other metals contained as impurities. This solution is subjected to electrolysis, copper-nickel anodes and copper cathodes being employed resulting in the deposition on the cathode of most of the copper. The nickel sulfate solution is treated with a chlorid of one of the alkaline earths forming a solution of nickel chlorid and a precipitate of a sulfate of the alkaline earth. The nickel chlorid solution is then subjected to electrolysis, an insoluble anode and a nickel cathode being employed, resulting in the deposit of the nickel on the cathode. The sulfur contained in the insoluble sulfate precipitate is separated with the formation of the chlorid of the alkaline earth, which may be used over again in the carrying out of the process.

In putting my process into practice I proceed as follows:—A matte containing the nickel and copper is obtained by any of the well known smelting and roasting methods at present in use for the treatment of nickel copper bearing ores. I take this matte and gently roast it in a revolving or reverberatory furnace in the presence of carbon and air in order to expel any remaining sulfur and arsenic contained therein. After this is effected the temperature of the furnace is increased in order to bring its contents into a molten condition. Part of the molten contents are cast into slabs, which are used as anodes in a part of the process subsequently described, and the remainder of the contents of the furnace are run into water and thereby disintegrated. The disintegrated material is treated with sulfuric acid in a dissolving tower, and a solution of copper and nickel sulfate obtained, with probably the sulfates of some other metals contained as impurities. This treatment is carried on until a saturated solu-

tion of the sulfates is obtained. This solution is now used as the electrolyte in a series of tanks, in which are suspended as anodes the slabs cast as above described, and which consist principally of metallic nickel and copper. To secure the best results, an electrolyte should be made from a matte from which the sulfur is not entirely expelled. Thin sheets of copper are used as cathodes. On passing an electric current through the electrolyte the copper is deposited on the cathodes as metallic copper, and an equivalent amount of copper and nickel is dissolved from the anodes. This process is continued through a series of tanks until finally a solution is obtained containing nickel sulfate and a small percentage of copper sulfate. This solution is now treated with a sulfid, either in the form of sulfureted hydrogen or in the form of a soluble sulfid, until the copper, iron, zinc, or other metals contained in the solution as impurities, have been precipitated as sulfids. When a sufficient quantity of these sulfids has accumulated they are worked up in any ordinary manner for the recovery of the copper.

The nickel sulfate solution is filtered, and is treated with a solution of a chlorid of an element of which the sulfate is insoluble. Chlorids of the alkaline earth such as calcium, barium, &c., will fill this requirement. This treatment results in the formation of a solution of nickel chlorid and an insoluble precipitate of a sulfate of the alkaline earth employed, which are separated by suitably filtering and washing. The nickel chlorid is now subjected to electrolysis, an insoluble anode, preferably graphite, and a nickel cathode, being employed. Metallic nickel is thus deposited at the cathode, and chlorin gas is liberated at the anode.

The sulfate of the alkaline earth obtained during the process is mixed with the requisite amount of carbonaceous matter, and roasted so as to convert it into sulfid, after which it is treated with the chlorin obtained as above, so as to convert it into the chlorid of the alkaline earth, with liberation of the sulfur which may be recovered, and converted into sulfuric acid for re-use in dissolving fresh quantities of copper-nickel matte.

What I claim as my invention is:—

1. In a process of reducing nickel from copper-nickel matte, the treatment of the matte with sulfuric acid to form sulfates of

the metals, the electrolysis of the solution with a copper-nickel anode and copper cathode to deposit the copper in the metallic form, and the treatment of the resultant nickel sulfate solution with a solution of a chlorid of an alkaline earth resulting in the formation of a solution of nickel chlorid and a precipitate of an insoluble sulfate of the alkaline earth.

2. In a process of reducing nickel from copper-nickel matte, the treatment of the matte with sulfuric acid to form sulfates of the metals, the electrolysis of the solution with a copper-nickel anode and copper cathode to deposit the copper in the metallic form, and the treatment of the resultant nickel sulfate solution with a solution of a chlorid of an alkaline earth resulting in the formation of a solution of nickel chlorid and a precipitate of an insoluble sulfate of the alkaline earth, and the electrolysis of the nickel chlorid with an insoluble anode and nickel cathode, resulting in the deposit of the nickel on the cathode and the liberation of chlorin gas.

3. In a process of reducing nickel from copper-nickel matte, the treatment of the matte with sulfuric acid to form sulfates of the metals, the electrolysis of the solution with a copper-nickel anode and copper cathode to deposit the copper in the metallic form, the treatment of the resultant solution with a sulfurizing re-agent to precipitate any remaining copper and other metals (present as impurities) in the form of sulfids, and the treatment of the resultant nickel sulfate solution with a solution of a chlorid of an alkaline earth resulting in the formation of a solution of nickel chlorid and a precipitate of an insoluble sulfate of the alkaline earth.

4. In a process of reducing nickel from copper-nickel matte, the treatment of the matte with sulfuric acid to form sulfates of the metal, the electrolysis of the solution with a copper-nickel anode and copper cathode to deposit the copper in the metallic form, the treatment of the resultant nickel sulfate solution with a solution of a chlorid of an alkaline earth resulting in the formation of a solution of nickel chlorid and a precipitate of an insoluble sulfate of the alkaline earth, the electrolysis of the nickel chlorid with an insoluble anode and nickel cathode, resulting in the deposit of the nickel on the cathode and the liberation of chlorin gas, the roasting of the sulfate of the alkaline earth obtained as above with carbon to convert it to a sulfid, and the treatment of the sulfid with the chlorin obtained as above to re-obtain the chlorid of the alkaline earth with the liberation of sulfur.

5. In a process of reducing nickel from copper-nickel matte, the electrolysis of a solution of copper-nickel sulfate with a copper-

nickel anode and copper cathode to deposit the copper in the metallic form, and the treatment of the resultant nickel sulfate solution with a solution of a chlorid of an alkaline earth resulting in the formation of a solution of nickel chlorid and a precipitate of an insoluble sulfate of the alkaline earth.

6. In a process of reducing nickel from copper-nickel matte, the electrolysis of a solution of copper-nickel sulfate with a copper-nickel anode and copper cathode to deposit the copper in the metallic form, the treatment of the resultant nickel sulfate solution with a solution of a chlorid of an alkaline earth resulting in the formation of a solution of nickel chlorid and a precipitate of an insoluble sulfate of the alkaline earth, the electrolysis of the nickel chlorid with an insoluble anode and nickel cathode, resulting in the deposit of the nickel on the cathode and the liberation of chlorin gas.

7. In a process of reducing nickel from copper-nickel matte, the electrolysis of a solution of copper-nickel sulfate with a copper-nickel anode and copper cathode to deposit the copper in the metallic form, the treatment of the resultant solution with a sulfurizing re-agent to precipitate any remaining copper and other metals (present as impurities) in the form of sulfids, the treatment of the resultant nickel sulfate solution with a solution of a chlorid of an alkaline earth resulting in the formation of a solution of nickel chlorid and a precipitate of an insoluble sulfate of the alkaline earth, and the electrolysis of the nickel chlorid with an insoluble anode and nickel cathode, resulting in the deposit of the nickel on the cathode and the liberation of chlorin gas.

8. In a process of reducing nickel from copper-nickel matte, the electrolysis of a solution of copper-nickel sulfate with a copper-nickel anode and copper cathode to deposit the copper in the metallic form, the treatment of the resultant nickel sulfate solution with a solution of chlorid of the alkaline earth resulting in the formation of a solution of nickel chlorid and a precipitate of an insoluble sulfate of an alkaline earth, the electrolysis of the nickel chlorid with an insoluble anode and nickel cathode, resulting in the deposit of the nickel on the cathode and the liberation of chlorin gas, the roasting of the sulfate of the alkaline earth obtained as above with carbon to convert it to a sulfid, and the treatment of the sulfid with the chlorin obtained as above to re-obtain the chlorid of the alkaline earth with the liberation of sulfur.

9. In a process of reducing nickel from copper-nickel matte, roasting the matte in the presence of carbon and air to expel any sulfur and arsenic remaining therein, the treatment of the roasted matte with sulfuric acid to form sulfates of the metals, the electrolysis of the solution with a copper-nickel,

anode and copper cathode to deposit the copper in the metallic form, and the treatment of the resultant nickel sulfate solution of a chlorid of an alkaline earth resulting in the formation of a solution of nickel chlorid and a precipitate of an insoluble sulfate of the alkaline earth.

10. In a process of reducing nickel from copper-nickel matte, roasting the matte in the presence of carbon and air to expel any sulfur and arsenic remaining therein, bringing the roasted matte into a molten condition, casting anodes from part of the molten mixture, disintegrating the remainder by running it into water, the treatment of the

disintegrated material with sulfuric acid to form sulfates of the metals, the electrolysis of the solution using an anode cast as above and a copper cathode to deposit the copper in the metallic form, and the treatment of the resultant nickel sulfate solution with a solution of a chlorid of an alkaline earth resulting in the formation of a solution of nickel chlorid and a precipitate of an insoluble sulfate of the alkaline earth.
